US0D1103217S

(12) **United States Design Patent** (10) **Patent No.:** **US D1,103,217 S**
(45) **Date of Patent:** **** Nov. 25, 2025**

(54) **VEHICLE ENGINE PLENUM**

(71) Applicant: **Bugatti International S.A.**,
Luxembourg (LU)

(72) Inventors: **Achim Anscheidt**, Berlin (DE); **Frank Heyl**, Calberlah (DE); **Jan Schmid**,
Luxembourg (LU)

(73) Assignee: **Bugatti International SA**, Luxembourg
(LU)

(**) Term: **15 Years**

(21) Appl. No.: **29/939,117**

(22) Filed: **Apr. 25, 2024**

(30) **Foreign Application Priority Data**
